UNITED STATES PATENT OFFICE

168,449

HAIR HOLDING CLAMP

John H. Honig, Long Beach, Calif.

Application February 8, 1952, Serial No. 18,445

Term of patent 3½ years

(Cl. D86—10)

To all whom it may concern:

Be it known that I, John H. Honig, a citizen of the United States, residing at 439 West 4th Street, Long Beach, California, county of Los Angeles, have invented a new, original, and ornamental Design for Hair Holding Clamp, of which the following is a specification, reference being had to the accompanying drawing, forming a part thereof.

Figure 1 is a side elevation of a hair holding clamp, showing my new design.

Figure 2 is a top plan view of the article as shown in Figure 1.

Figure 3 is a perspective view of the same.

I claim:

The ornamental design for a hair holding clamp, as shown.

JOHN H. HONIG.
